PIANO KEY EASING MACHINE

Mason A. Jacobson and Harold J. McGetrick, De Kalb, Ill., assignors to The Rudolph Wurlitzer Company, Chicago, Ill., a corporation

Application January 25, 1951, Serial No. 207,778

7 Claims. (Cl. 100—49)

This invention relates to a piano key easing machine for providing the felt lined slots of a key opening with proper and accurate pin clearance.

The standard piano keyboard comprises a plurality of pine or bass wood keys, each having a slotted opening at the balance point and another slotted opening at the front which projects into the bottom of the key. Both slotted openings have their side walls lined with felt. Each key is inserted over a pin at the balance point of the keyboard so that when the key is depressed the front pin of the keyboard extends into the slotted opening at the front of the key.

In the standard keyboard there are 88 keys and it is necessary in the process of regulating the piano for proper playing that correct and accurate clearance be obtained between the walls of the slotted openings for the balance pin and the front pin. To achieve this end, the accepted procedure is to "ease" each key at the balance point and front opening by means of special hand manipulated pliers, which the regulating mechanic inserts in the slotted openings of the key to compress the felt and the wooden wall by hand until he is satisfied through feel or touch that the correct clearance is obtained. Such hand manipulating method is not only tiring and requires an expert mechanic of long experience and training but is non-uniform because the mechanic finds it difficult to maintain the same amount of compression on the felt and wooden walls at all times, particularly during the later fatiguing hours of the work day.

It is therefore the object of this invention to provide a simple and effective machine for easing piano keys which may be manipulated by inexperienced help, and wherein the easing operation is at all times uniform and accurate by applying the same amount of compression to each key wall. This is accomplished by providing a pair of spreaders which not only engage and compress the felt and wooden walls of the key opening to a predetermined and exact extent, but maintain them under compression during a predetermined time period for effecting the accurate setting thereof.

The full nature of the invention will be understood from the accompanying drawings and the following description and claims:

Fig. 1 is a perspective view of the machine with parts removed, parts broken away and parts schematically illustrated.

Fig. 2 is a central vertical section through the clamping jaws and spreaders with a piano key in processing position.

Fig. 3 is a perspective view of the time control mechanism.

Fig. 4 is an enlarged view partially in section, and parts removed, showing the spreaders in easing engagement with a piano key.

Fig. 5 is the same as Fig. 4 showing the spreaders in released position.

In the drawings there is illustrated a piano key easing machine having a supporting base 10 and a housing 11 mounted thereon. Supported on top of the housing there is a bed plate 12 carrying on opposite sides thereof in opposed spaced relation a set of guide blocks 13. Slidably between each pair of guide blocks there is a clamping slide 14 bifurcated at one end thereof. Each of said clamping slides carries a clamping jaw 15 pivotally connected thereto adapted to engage and clamp a piano key 16 therebetween as shown in Figs. 2 and 4.

Mounted below the bed plate 12 there is provided a cam head 17 having outwardly extending opposed cam

surfaces 18 terminating in an inwardly formed recess portion 19 extending thereabove. The cam head is carried by a piston rod 20 extending into an air cylinder 21 in which a piston indicated at 22 connected with the piston rod is cause to operate through air pressure. Bolted to the underside of the bed plate, as at 12a to extend downwardly therefrom, there is a mounting bracket 23 having laterally extending bifurcated arms 24 and a lower guide portion for slidably receiving the cam head 17.

Fulcrumed intermediate the arms 24 on each side of the bracket there is a clamping lever 25. The lower end of each lever is provided with a pair of cam rollers 26 normally riding in the recessed portion 19 of the cam head when in its lowered position, and upon the outwardly extending cam surfaces 18 when in its raised position.

The upper ends of the clamping levers are formed with the actuating fingers 27 each extending through a slot 28 in the bed plate into the bifurcated ends of the clamping slides 14 respectively. The actuating fingers of each of said levers is urged outwardly, and the rollers inwardly to bear upon the cam surface by the compression springs 29. Said springs are interposed between the upper portion of each lever and the adjacent portion of the bracket 23.

When air is forced into the cylinder 21 the cam head is raised to spread the cam rollers 26 and force the fingers 27 toward each other for causing the clamping jaws to engage and clamp the piano key 16 therebetween. When air is exhausted from the cylinder the cam head drops by gravity due to its weight so that the cam rollers ride into the recessed portions 19 of the head permitting the springs 29 to spread the actuating fingers and clamping jaws 15 for releasing the piano key.

In axial alignment with the piston rod 20 and slidably mounted in the bracket 23 there is a spreader holder 30. The lower end of said holder abuts an adjustable thrust screw 31 carried by the cam head. Fulcrumed at the upper end of the spreader holder are the spreaders 32, each having an upwardly extending lip portion 33 and a laterally extending arm portion 34, the fulcrum point of the spreader being intermediate the lip and arm portions.

Each spreader is also formed with the downwardly extending tail portion 35, and between said tail portions and supported therein there is a compression spring 36. The lip portions of the spreader extend upwardly through an aperture in the bed plate between the clamping jaws and in position to enter the slotted opening 16b of the key 16. The underside of the bed plate is provided with a pair of stops 37 arranged for engagement by the extended ends of the respective arm portion 34 of the spreader.

The above described arrangement of the spreader is such that when the cam head is elevated it causes the key to be gripped by the jaws 15, the adjustable thrust screw 31 engages the spreader holder 30 and moves the holder and the spreaders upwardly to cause the lip portions 33 to freely enter the slotted opening of the key. After the lip portions have thus entered the key, continued movement of the cam head and spreader holder causes the laterally extending arm portions 34 to engage their respective stops 37.

The final upward thrust, through the medium of the arms and stops, causes the lip portions to spread laterally to a predetermined distance into compressing engagement with the felt 16a glued to the wooden wall of the slotted opening. Thus the slotted opening and felt is "eased" to a predetermined extent. This easing engagement thereof then continues for a predetermined time as further described.

The machine is connected with a source of compressed air not shown, connected through a pressure switch 40 with a high pressure air line 41. Said high pressure air line is controlled by an air solenoid valve mounted within the valve housing 42 which in turn is connected through the air line 43 with the underside of the air cylinder 21. The air solenoid valve is also connected with an exhaust air line 44. Said air solenoid valve is controlled through an electric circuit from a relay and timer schematically indicated in the housing 45. Said relay and timer is actuated by a micro-switch 46 (Fig. 3) in the usual manner.

The above described air control and timing is merely illustrated schematically in that any of the well known

and understood air solenoid valves, relay and timers, pressure and micro-switches may be employed in the relation shown.

The micro-switch is actuated by a control lever 47 fulcrumed to a suitable boss on the housing 11. The inner end of the lever is connected with a control rod 48 having its upper free end extending through and guided within an opening 49 in the bed plate 12 immediately below the piano key to be engaged thereby and pressed downwardly when the key is placed in operative position. The relay and timer is set to reverse the air solenoid valve indicated at 42 at a predetermined time after the operating cycle is initiated through actuation of the micro-switch by pressing the key in operative position. The timing is predetermined to effect maintenance of the spreading and compressing action in the slotted opening to permit the compressed felt and wood to set.

In operation, when a piano key is placed in position on the bed plate, as shown in Figs. 2 and 3, the control rod 48 is pressed downwardly by the key causing the micro-switch to start the timer and open the air solenoid valve to admit air into the cylinder 21. Thus the cycle and timing of the operation is initiated. The cam head 17 is forced upwardly causing the jaws 15 to clamp the key. Thereupon the arm portions 34 of the spreader are forced upwardly by the holder 30 through screw 31, into engagement with the stops 37 causing the lip portions 33 thereof to move outwardly into spreading and compressing engagement with the felt lined walls of the slotted opening 16b in the key 16.

The extent of the spreading and compressing action has been predetermined by the setting of the adjustable thrust screw 31. After a predetermined time interval in which the spreading and compressing action has been maintained, the relay and timer indicated at 45 actuates the air solenoid valve 42 to shut off the air source through the line 41 and open the line 43 to the exhaust line 44 for exhausting air from the cylinder 41. The cam head then drops releasing and withdrawing the spreaders and opening the clamping jaws for removal of the key. It will therefore be observed that during the cycle of operation the felted slotted opening in the key will have received a predetermined spreading and compressing force over a predetermined time interval to effect the setting thereof.

The invention claimed is:

1. A piano key easing machine including means for securing a piano key having a felt lined slotted opening therein operative position on said machine, a spreader including lips mounted on said machine adapted to extend into the felt lined slotted opening of the positioned key for deforming the same, and power operated mechanism operable to force said spreader against opposite walls of the slotted opening to a predetermined extent and over a predetermined time interval for permanently establishing the deformation of the felt and key and means operable by positioning of the key in operative position on said machine for receiving said spreader to initiate said power operated mechanism.

2. A piano key easing machine including means for securing a piano key having a felt lined slotted opening therein in operative position on said machine, a spreader including lips mounted on said machine adapted to extend into the felt lined slotted opening of the positioned key for deforming the same, power operated mechanism operably connected with said spreader to force it against opposite walls of the slotted opening to a predetermined extent, and a time control means connected with said mechanism for maintaining said spreader in its spreading position for predetermined time interval to permanently establish the deformation of the felt and key and to release said spreader for disengagement from said walls at the conclusion of said time interval.

3. A piano key easing machine including a pair of clamping jaws positioned to clamp a key placed therebetween, a spreader including lips mounted to extend between said jaws into a felt lined slotted opening in the positioned key for deforming the same, and power operated mechanism initiated by the positioning of the key between said jaws to effect a clamping action of said jaws and force said spreader against opposite walls of

the slotted opening to a predetermined extent and over a predetermined time interval to permanently establish deformation of the felt and key.

4. A piano key easing machine including a pair of clamping jaws positioned to clamp a key placed therebetween, said key being provided with a slotted opening having felt lined walls, a pair of spreaders including lips mounted to extend between said jaws into said opening, power operated mechanism operably connected with said jaws and spreaders to effect a clamping action of said jaws and force said spreaders against opposite walls of the slotted opening to a predetermined extent for deforming said walls, a time control element positioned to be engaged upon the key being placed between said jaws for initiating operation of said mechanism, and a time control for effecting and maintaining said clamping and spreading action over a predetermined time interval for permanently establishing deformation of said walls, said time control being operable to release said jaws and spreader to permit removal of said key at the completion of said time interval.

5. A piano key easing machine including a bed plate for receiving a piano key having a felt lined slotted opening therein, a pair of clamping jaws positioned to clamp said key therebetween, a pair of spreaders including lips mounted to extend through said bed plate into the opening of said key, a cam head movable into camming engagement with said jaws, a spreader holder movable by said cam head to force said spreaders laterally against opposite walls of the slotted opening to a predetermined extent, and power operated mechanism adapted to move said cam head into camming position to effect the clamping action of said jaws and maintain said spreaders in position to compress the opposite walls of the slotted opening to a predetermined extent.

6. A piano key easing machine including a bed plate for receiving a piano key having a felt lined slotted opening therein, a pair of clamping jaws positioned to clamp said key therebetween, a pair of spreaders mounted to extend through said bed plate into the opening of said key, a cam head movable into camming engagement with said jaws, a spreader holder movable by said cam head to force said spreaders laterally against opposite walls of the slotted opening to a predetermined extent, power operated mechanism adapted to move said cam head into camming position to effect the clamping action of said jaws and maintain said spreaders in position to compress the opposite walls of the slotted opening to a predetermined extent, and a time control for said mechanism for causing it to release said spreaders and jaws after a predetermined time interval.

7. A piano key easing machine including a bed plate for receiving a piano key having a felt lined slotted opening therein, a pair of clamping jaws positioned to clamp said key therebetween, a pair of spreaders mounted to extend through said bed plate into the opening of said key, a cam head movable into camming engagement with said jaws, a spreader holder movable by said cam head to force said spreaders laterally against opposite walls of the slotted opening to a predetermined extent, an adjustable abutment between said cam head and spreader holder for adjustably determining the extent of the spreading action, and power operated mechanism adapted to move said cam head into camming position to effect the clamping action of said jaws and maintain said spreaders in position to compress the opposite walls of the slotted opening to a predetermined extent.
